[57] **CLAIM**

The ornamental design for a waffle iron plate, as shown.

DESCRIPTION

FIG. 1 is a perspective view of a waffle iron plate showing
my new design;

FIG. 2 is a top plan view thereof;

FIG. 3 is a bottom plan view thereof;

FIG. 4 is a front elevational view, the rear, left and right
side elevational views being identical;

FIG. 5 is a cross-sectional view taken along line 5—5 in
FIG. 2; and,

FIG. 6 shows a top plan view of a second embodiment
of my new design.

The bottom and side views of the second embodiment
are the same as shown in FIGS. 3 and 4.
